(57) **CLAIM**

The ornamental design for a syringe plunger, as shown and described.

DESCRIPTION

FIG. 1 is a front perspective view of a syringe plunger, showing my new design in a collapsed configuration and in condition of use;

FIG. 2 is a front elevation view of FIG. 1;

FIG. 3 is a rear elevation view of FIG. 1;

FIG. 4 is a right side view of FIG. 1;

FIG. 5 is a left side view of FIG. 1;

FIG. 6 is a top view of FIG. 1;

FIG. 7 is a bottom view of FIG. 1;

FIG. 8 is a cross-sectional view of FIG. 1 taken along line 8-8 of FIG. 4;

FIG. 9 is a front perspective view of the syringe plunger in an extended configuration;

FIG. 10 is a front elevation view of FIG. 9; the rear elevation view being a mirror image of the front elevation view;

FIG. 11 is a right side view of FIG. 9; the left side view being a mirror image of the right side view;

FIG. 12 is a cross-sectional view of FIG. 9 taken along line 12-12 of FIG. 11;

FIG. 13 is a perspective view of the syringe plunger of FIG. 2, shown exploded for clarity of disclosure;

FIG. 14 is a top view of the bottom half of the syringe plunger taken from line 14-14 in FIG. 13 directionally downward; and,

(Continued)

FIG. 15 is a bottom view of the top half of the syringe plunger taken from line 15-15 of FIG. 13 directionally upward.

In FIG. 1, the broken lines showing a syringe barrel depict environmental structure and form no part of the claimed design. In all of the drawings, the elements shown in broken lines at the base of the plunger depict portions of the syringe plunger that form no part of the claimed design. All broken lines form no part of the claim.
